UNITED STATES PATENT OFFICE.

MARY STARMER, OF NEWPORT NEWS, VIRGINIA.

BELT BUCKLE.

Application filed December 30, 1921. Serial No. 525,887.

To all whom it may concern:

Be it known that I, MARY STARMER, a citizen of the United States, residing at Newport News, in the county of Warwick and State of Virginia, have invented certain new and useful Improvements in Belt Buckles, of which the following is a specification.

The buckle of the present invention is especially adapted for use in connection with belts or garment supporters of the waist-line type, for use by both men and women, and is designed particularly to provide a buckle for connecting the ends of the belt, in which buckle the parts may quickly be connected or attached, and by means of which the buckle may with equal facility be disconnected. By the utilization of my invention stitching and sewing of parts are eliminated and the complementary members of the fastening device are secured at the ends of web or belt by pin fasteners in order that the length of the belt or web may readily be adjusted and the complementary members of the buckle be securely retained on the belt ends. When the complementary members of the buckle are fastened together, the connection is securely made and danger of displacement or loosening of parts is eliminated.

In the accompanying drawings I have illustrated one complete example of the physical embodiment of my invention wherein the parts are combined and arranged according to one of the best modes I have thus far devised for the practical application of the principles of my invention, wherein the buckle is combined with a waist-line belt, adapted for use by men or women, as a garment supporter.

Figure 1 is a front view of the buckle shown as connecting the ends of a belt.

Figure 2 is a rear view of the belt ends and connected buckle.

Figure 3 is a horizontal sectional view through the buckle and connected web ends.

Figure 4 is a rear view of the buckle plate.

Figure 5 is a view of the buckle fastening-link.

The ends 1 and 2 may be of fabric, leather, or other suitable material adapted for belts, and the buckle as a whole, for connecting these ends is indicated by the numeral 3 in Figure 1. The buckle, or buckle-plate 3 as hereinafter mentioned, is preferably of rectangular shape as shown and stamped or pressed from sheet metal, preferably curved

as shown to conform to the rotundity of the waist when used with a belt for adjustment about the waist. At one end the buckle-plate is fashioned with an integral, rear, slotted, guide plate 4, and at its opposite end at the rear, a rear-plate 5 is turned back upon the buckle-plate and lies parallel therewith within the top and bottom horizontal flanges 6, 6, formed at and turned back from the respective edges of the buckle-plate. As best seen in Figure 4 the rear plate is fashioned with a U-shaped slot 7, turned on edge, to form a horizontally disposed locking tongue 8, and as the metal of the plate is resilient and elastic, this tongue may with facility be flexed without losing its required degree of rigidity. In addition to the U-shaped slot, the rear plate is provided with an additional slot 9 extending vertically of the plate, to form an end attaching bar 10, for the web or belt end 1. To accommodate the belt end 1, the guide plate 4, which connects the top and bottom flanges 6 of the buckle plate, is provided with an open slot 11 through which the belt end is passed, and the formation of the slot 11, as seen in Fig. 4 provides a supporting bar 12 having notches 12' therein at the extremity of the rear of the buckle plate.

The end 1 of the belt is passed through the slot 11, back of the bar 10, and through slot 9, and is then formed with a loop 13, and the loop is secured by means of a somewhat U-shaped pin-fastener comprising a bar 14 that is supported on the bar 12 in notches 12'. Arms 15 are projected from the pin bar, between the looped end of the belt end 1 and the back of the buckle-plate, and the prongs 16 on the extremities of these arms are passed through the material of the loop to fasten the looped end. In this manner the looped end is attached to the rear portion of the buckle plate, beyond its center line, by means of the bar 10, and guided or retained by the slot 11 and plate 4, in order that the buckle will withstand the pull required in buckling the belt, and the buckle will lie in easy and comfortable position for the wearer, and present a neat appearance, at the front.

The fastening link 17 is also stamped from a sheet of metal that is preferably resilient or elastic to the required degree for performing its functions, and is fashioned with a vertical slot 18 to provide an attaching bar 19 for the loop 20 formed at the end

2 of the belt. A pin fastening device 21 is utilized to secure this loop at the belt end. The device 21 made of a single piece of wire with an anchoring bar, and a pair of pins or prongs at its ends, is adapted for use as adjusting buckle for slidable movement on the belt 2 when adjusting the length of the belt. The belt end is passed through the slot 18, and when in properly adjusted position the adjuster 21 retains the loop as shown in the drawing forming a neat appearance and flat joint capable of facile manipulation when adjustment is required.

The link 17 is slotted at 22, 22, and these parallel slits form a resilient or spring bar 23 for co-action with the tongue or hook 8 on the rear plate 5 of the buckle plate.

It will be seen that the parts of the buckle connection are compactly arranged within the enclosure formed by the buckle plate and its flanges 6, and a comparatively flat structure is formed at the belt ends, which results in a comfortable garment supporter, and presents a neat appearance. The face of the buckle-plate may be engraved or otherwise ornamented and is capable of receiving a high polish, or may be provided with a dull finish as desired. In connecting the parts the link 17 is slipped over the tongue or hook 8, the slits in the link permitting the bar 23 to slip over the hook between the hook and the buckle plate, and the remaining portion of the link sliding over the outside of the hook. The hook and the bar 23 are thus slightly bent and the hook is frictionally clasped within the link members, and of course a strain or pull on the belt end 2 results in

more firmly securing the link in coupled position on the hook. When unbuckling the belt, the link is slipped to the left in the drawings and released from the hook, and the parts may then be separated.

Having thus fully described my invention, what I claim as new and desire to secure by Letters Patent is:—

1. The combination with a buckle plate having a rear plate and a hook and a slot fashioned therein, a slotted guide plate, a belt end passed through the guide plate and looped through the slot in the rear-plate, a supporting bar in the guide plate, a barbed fastener carried by said supporting bar and securing the looped end of the belt, and a coupling link slotted to engage said hook.

2. The combination with a buckle plate having top and bottom flanges, a rear plate within said flanges having a hook and a slot therein to receive a looped belt end, and a slotted guide plate on said buckle plate, of means supported on said slotted guide plate for securing said looped belt-end, and a coupling link for another belt end adapted to engage over said hook.

3. The combination with a buckle plate having top and bottom flanges, a rear plate having a hook and slot to receive a looped belt-end, and a slotted guide plate formed with a notched supporting bar, of a slotted coupling link for attachment to said hook at one end of a belt, and a U-shaped barbed fastener carried by said notched supporting bar for engagement with the first mentioned looped belt-end, as described.

MRS. MARY STARMER
